UNITED STATES PATENT OFFICE.

JOHN COFFIN, OF JOHNSTOWN, PENNSYLVANIA, ASSIGNOR TO THE CAMBRIA IRON COMPANY, OF SAME PLACE.

PROCESS OF TOUGHENING AXLES.

SPECIFICATION forming part of Letters Patent No. 391,120, dated October 16, 1888.

Application filed March 3, 1888. Serial No. 266,016. (No model.)

To all whom it may concern:

Be it known that I, JOHN COFFIN, of Johnstown, in the county of Cambria and State of Pennsylvania, have invented certain new and useful Improvements in Processes of Toughening Steel Axles or other Steel Bars; and I do hereby declare the following to be a full, clear, and exact description of the invention, such as will enable others skilled in the art to which it appertains to make and use the same.

My invention relates to an improvement in processes for toughening steel axles or other bars of steel.

In the manufacture of steel axles that have been hammered or otherwise manipulated to give them form it has been found of great advantage to reheat the axle after it has been completed as a forging, then partially cool it in a bath of water or other proper cooling mixture, and, after it has received a surface chill of proper depth, to remove it from the bath and allow it to gradually cool in an unexposed situation by a free contact of the atmosphere. When an axle is treated as above mentioned, there is a rearrangement of molecular structure throughout its body, which removes crystallization, toughens the material, and renders the axle less liable to breakage when it is exposed to sudden strains of a percussive or torsional nature.

My present improved method of toughening steel axles or other bars of steel consists, essentially, in the reheating of the article to be treated, so as to give it an even distribution of heat throughout its mass, then lowering it on mechanism located in a bosh or stationary water-trough that has been previously filled or partially filled with water or other cooling-liquid, and then rotating the axle within this water-tank while it is submerged by the action of the contained apparatus on which it is placed. After the axle has been sufficiently chilled it is removed and allowed to cool off by diffusion of the contained heat from the core to the surface and its radiation, owing to contact with the atmosphere.

My present method of toughening steel axles further consists in the reheating of the axle after it has been forged or otherwise manufactured, then lowering it by proper means into a bosh or water-trough containing water or other cooling-liquid, to place it upon a mechanism located within the bosh, that

rapidly rotates the axle, and while in this position submerged and revolving under water to spray upon its surface a series of forcible jets of cooling-liquid, that agitates the water, and thus prevent the spheroidal formation which would retard heat dissipation, and, finally, when the axle has received a surface chill of sufficient depth that leaves a highly-heated core therein, it is removed from the bath and left to get entirely cold by contact with the air in a dry place.

Different mechanical devices may be employed to put in practice my improved process or method for toughening steel axles, as it is evident that numerous plans of construction may be provided to give the axle a rotative motion after it has been submerged in cooling-liquid in the bosh; and it is also apparent that the axle may be lowered by different methods into the liquid in the bosh and upon its cradle or rotating devices—as, for instance, the reheated axle may be gripped by tongs and lowered manually; or it may be hung in gripping-hooks from a swinging crane, by which it may be swung into position and then lowered through the water onto the rotary cradle, and, finally, by a preferred means, which consists in transporting the reheated axle from the place where it is heated to the stationary bosh and roll it down inclined trackways onto the revolving apparatus. This latter plan of construction will now be described.

In the drawings, Figure 1 represents a plan view of the stationary bosh and contained apparatus, a portion being removed between broken lines near its center of length that it is not important to show. Fig. 2 is an end elevation of the device, taken on the line X X, Fig. 1.

A represents a stationary water-chamber or bosh, which is placed upon a suitable foundation, to which it is secured by bolts that pass through the perforated ears a. The walls of the bosh A are of such a height as to allow a considerable volume of cooling-liquid, preferably cold water, to be contained therein or up to the overflow-orifice h. (See Fig. 2.) Upon one side of the bosh the wall is projected outwardly and upwardly to form an overhanging lip or shoulder-extension, which is of the full length of the bosh and has an inclined bottom, as shown in Fig. 2, this sloping bottom descending diagonally inward from a point, i',

near the upper edge of the outer wall, *i*, to a point, *k*, where it joins the vertical wall *A*² of the rectangular chamber or bosh *A*, said wall *A*² being about one-half the height of the opposite side wall, *A*³.

Within the bosh *A*, a proper distance above its bottom surface, the two mating shafts *B* *C* are supported parallel to each other by an engagement of their ends within the perforated bosses *b* *c*, which are made to project from the sides of two flat plates, *J*, that are secured to the inner surfaces of the end walls, *A'*, of the bosh by bolts *d*.

The shaft *B* has rounded journals on its ends to adapt it to revolve on its supporting-bosses *b*, that may be constructed as boxes to receive each end of said shaft. The parallel shaft *C* is held rigidly in its end supports by pinning or keying it fast to them, a proper distance intervening between these shafts to allow the location thereon of parts that will now be described.

Upon the shaft *B*, preferably near the boss or box *b* at one end of the bosh, a sprocket-wheel, *D*, is mounted and firmly fastened to said shaft, this wheel being engaged by an endless sprocket-chain, *I*, which latter extends upwardly a sufficient distance to be placed upon a mating sprocket-wheel (not shown) that is adjusted upon a driving shaft which is adapted to revolve by applied power under control of an operator, and thus permit the rapid revolution of the shaft *B* in a proper direction when desired.

At proper distances apart on the shaft *B* several hubs, *e*, are rigidly secured. These have a central radial rib, *e'*, projecting from their central portion to adapt them to have contact with an axle or other round bar.

Upon the shaft *C*, at points directly opposite the radial projections *e'*, formed on the hubs *e*, short revoluble wheels *f*, of the same diameter as the ribs *e'*, are held in place by fixed collars *g*, to permit the wheels to revolve freely when actuated by frictional contact of their peripheral surfaces with a revolving axle placed on them.

Beneath the shafts *B* *C*, and midway between them, the spray-pipe *K* is placed. This extends throughout the length of the bosh *A* and projects water-tight through one of the end walls, *A'*, to be extended outside of the bosh and be connected to any adequate water-supply that will afford a volume of water with proper pressure to forcibly project the water in sprays from the upper surface of the pipe *K*, which is perforated on its upper surface, one or more rows of spaced holes being formed thereon, as shown in Fig. 1.

Upon the inclined bottom of the lip *G* of the bosh *A* two or more guideways or upwardly-projecting track-bars, *H*, are formed or adjusted. These are intended to permit an axle to roll from their outer ends downward to assume a position between the wheels *f* of the shaft *C* and the fixed hubs *e*, or rather the projecting ribs *e'* of these hubs; and it should

be stated that these wheels and ribs are not in contact, but in close proximity to each other.

The height of the guideways *H* and degree of inclination given to them are such in relation to the position of the shafts *B* *C* and their wheels and hubs that the top edges of the guideways at their inner ends will be about 75 in the same horizontal plane with the upper peripheral edges of the wheels *f*, so that an axle will roll down the ways and upon the cradle formed by the adjacent wheels *f* and hubs *e*.

In operation of the devices the bosh *A* is filled to the lower edge of the overflow-hole *h*, or near the upper edge of the vertical walls of said chamber. The shaft *B* is made to rotate by the sprocket-wheel and chain-gear in 85 the direction indicated by the arrow in Fig. 2. This will revolve the axle *S* in the same direction of motion it obtains by rolling down the inclined ways *H*, so that its momentum thus derived will have effect to aid the operation of the revolving hubs or shaft *B*, which will quickly increase the rotary motion of the axle until its speed is equal to that of the driving-hubs *e*. Simultaneously with the immersion of the axle in the bosh, as has been described, the spray-pipe *K* is put in use, and jets from it are forcibly projected from its perforations upon the revolving axle, which will aid the operation of cooling it rapidly, as has been previously mentioned. At a proper stage 95 of cooling the axle *S* is removed from the bath and located in a place that will allow it to be in contact with the atmosphere and protect it from dampness or contact with wet ground on one side, which would have a tendency to 105 warp it and prevent regularity of cooling that is effected by an even diffusion of contained heat that passes through the chilled portion of the axle from the core to the surface of the same.

Having fully described my preferred form of construction of machinery to carry into effect my improved process for toughening steel axles or other round steel bars, what I claim as new, and desire to secure by Letters Patent, is—

1. The within-described method of cooling a steel axle or other steel bar to toughen it, consisting in lowering it in a bath of cooling-liquid, then connecting it with rotating devices that rapidly revolve it while being cooled.

2. The method of cooling an axle or other steel bar to toughen it, consisting in immersing it in a cooling-bath by rolling it down an incline, and then connecting it with a revolving mechanism which will maintain its rotation while cooling.

In testimony whereof I have signed this specification in the presence of two subscribing witnesses.

JOHN COFFIN.
